UNITED STATES PATENT OFFICE.

CHARLES L. GOODEUM, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,250,116.

Specification of Letters Patent. Patented Dec. 11, 1917.

Application filed October 11, 1916. Serial No. 124,949.

To all whom it may concern:

Be it known that I, CHARLES L. GOODRUM, a citizen of the United States, residing at Brooklyn, in the county of Kings and State 5 of New York, have invented certain new and useful Improvements in Telephone-Exchange Systems, of which the following is a full, clear, concise, and exact description.

This invention relates to telephone exchange systems employing machine switching, and particularly to such systems where in a connection leads through a plurality of offices.

It may happen that the calling party desires to speak with a second party in the distant office immediately after having concluded his conversation with the first party. Heretofore, in order to establish a connection with the second party's line, the calling 20 party had to reset all the switches involved in the connection.

In the circuit arrangement of this invention, if the calling party desires to establish a connection with such second party's line, 25 he can release the switches in the distant office while retaining the switches in the originating office in their set condition and reset a train of switches at the distant office to connect with the line of such second party.

The invention is illustrated in connection 30 with a fast and slow two-wire system. In such systems the connector is provided with one fast relay and two slow relays. When the connection has been built up as far as 35 the connector, the fast relay thereat is energized in a circuit controlled at the substation sender. The fast relay controls the first slow relay at a front contact, and the second slow relay is controlled at a back contact of 40 the fast relay and a front contact of the first slow relay. These relays are operated by the sender to transmit impulses to the connector stepping magnets to set the connector on the wanted line. When the called party responds, 45 an electroresponsive switching device, such as a side switch, advances and prepares a release circuit for the switches preceding the connector at the called office. If the calling party, after setting up the connection and concluding the conversation, de-

sires to talk with another party in such office, he actuates a switch at his substation, preferably the sender, which momentarily deenergizes the fast relay. The fast relay in deenergizing closes a circuit for the second slow relay over the front contact of the first slow relay. The second slow relay in energizing causes the closure of the release circuit referred to.

Referring to the drawing, Figures 1 and 2 taken together show a circuit arrangement embodying the invention. The invention will be best understood by describing in detail the operation.

Upon the removal of the receiver at substation A, a line finder (not shown) is automatically set in motion and extends the calling line to the first selector S, whereupon the stepping relay 100 thereat is energized over the calling line circuit, and in attracting its armature, energizes a slow relay 101. This relay, in attracting its armature, interposes a break in the circuit of release magnet 102 of the first selector S. The calling party now operates his sender s to transmit the first digit of the wanted number. This sender may be of the well-known type which interrupts the line circuit a number of times corresponding to the particular digit involved. Upon each retraction of the armature of relay 100 an impulse is transmitted over the following circuit to the primary stepping magnet 103 of the first selector S, armature and back contact of relay 100, armature and front contact of relay 101, off-normal contact 104, magnet 103, free pole of battery. The primary magnet 103 thus steps the brushes into operative relation to the desired group of trunks. Upon the first retraction of the armature of relay 100, a slow relay 105 is energized, and, in attracting its armature, energizes the escape magnet 106, which is constructed to release the side switch from position 1 to position 2, upon its deenergization. When the sender s restores and maintains the line circuit closed, the relay 105, after an interval, retracts its armature, deenergizing the escape magnet, which thereupon releases the side switch into position 2. In position 2 the following cir- 100

cuit is closed for the secondary magnet 107 to drive the brushes 108, 109 and 110 over the level in which two wire trunks leading to the desired distant office terminate. This circuit is as follows: free pole of battery, magnet 107 and its armature and back contact, side-switch arm 114 to ground at the armature and front contact of relay 100, now energized over the line circuit. Idle trunks 10 are those upon whose test multiples 113 ground is present, and the escape magnet 106 is arranged to release the side switch into position 3 upon its energization. In position 2 the escape magnet 106 is connected to 15 the test brush 110 over side-switch arm 115. When such test brush encounters a grounded multiple 113, therefore, it becomes energized, releasing the side switch into positions 3, the side-switch arm 114 in passing 20 out of position 2 opening the circuit of secondary stepping magnet 107, thus stopping the selector upon the seized trunk. In position 3 the repeating relay 150 in the seized trunk is energized over the calling 25 line circuit, and in attracting its left armature removes ground from test multiple 113 of the trunk to render the same busy. The attraction of this armature also closes the circuit of a slow relay 151, which interposes 30 a break in the circuit of release magnet 102 of selector S. Since this relay is slow to release its armature, the vibration of the armature of the relay 150, when operated by the sender will not affect the release magnet 102. Relay 150 in energizing closes the 35 following circuit for stepping relay 118 of such selector at the distant office over the trunk conductors 152, 153: free pole of battery at the distant office, right winding of relay 118 thereat, arm 137 and the first contact of the side switch, conductor 152, upper right winding of repeating coil RC, armature and front contact of relay 150, lower right winding of repeating coil RC, conductor 153, arm 138 and first contact of the 45 side switch, left winding of relay 118, to ground. Relay 118 in energizing closes the circuit of a slow relay 121 which in attracting its armature interposes a break in the 50 circuit of release magnet 123 of the selector S' and connects the primary magnet 124 of such selector to the back contact of stepping relay 118. The selector S' is now ready to receive the impulses. Upon the operation 55 of the sender by the calling party in transmitting the next digit, the armature of relay 150 vibrates and upon each retraction of the left armature thereof relay 118 transmits an impulse to magnet 124 to step the brushes 126, 127 and 128 into operative relation to the desired group of the trunks 129, 130 and 131, which may terminate in a connector C, or another selector similar to S'. Upon the 60 first retraction of the armature of relay 118, a slow relay 132 is energized, and in attracting its armature energizes the escape magnet 133 of selector S', which magnet is constructed to release the side switch from position 1 to position 2 upon its deenergization. When the sender s restores, it maintains the 70 line circuit closed. The maintained energization of relay 118 causes the slow relay 132 to retract its armature, thus deenergizing the escape magnet which passes the side switch into position 2. In position 2, the 75 secondary stepping magnet 134 drives the brushes 126, 127 and 128 over the selected trunk group due to the closure of the following circuit: free pole of battery, magnet 134, its armature and back contact, arm 135 and 80 its second contact, armature and front contact of relay 118 to ground. As in the case of selector S, idle trunks are those upon whose test multiples 131 ground is present. Consequently, when the test brush 128 encounters a grounded test multiple 131, the escape magnet 133 becomes energized over a 85 circuit including the arm 136 and its second contact and test brush 128. The escape magnet is constructed to release the side switch 90 from position 2 to position 3, upon its energization. In moving out of position 2, the side-switch arm 135 opens the circuit of the secondary stepping magnet 134, thus stopping the selector with the brushes 126, 127, 95 128 upon the terminals of the seized trunk. In position 3 side-switch arms 137, 138 extend the calling line to the connector C, Fig. 2, cutting off the bridge at the second selector containing the stepping relay 118. In 100 moving into position 3, arm 120 extends the circuit of release magnet 123 to release conductor 139 extending to the connector. The ground upon this conductor at the armature and back contact of stepping relay 7 is removed before the release magnet 123 can energize. 105 Relay 7 is energized over the conductors 152, 153, and at its armature and front contact, energizes a slow relay 8. This relay, in attracting its right armature, interposes a break in the circuit of the test conductor 9 leading back to the preceding switch, and in attracting its left armature interposes a 110 break in the circuit of the release magnet RM of the connector. 115 The calling party now operates his sender s to transmit the tens digit of the wanted number, to position a set of brushes 16, 17, 18 in operative relation to the group of 120 multiples containing those of the wanted line. Upon each retraction of the armature of relay 7, as repeating relay 150 retracts its right armature, an impulse is transmitted to the primary magnet 10 of the connector over the following circuit: armature and back contact of relay 7, right armature and front contact of relay 8, which is slow- 125

acting and does not deenergize as its circuit is momentarily interrupted at the front contact of relay 7, conductor 11, connector side switch arm 3, magnet 10, free pole of battery. Upon the first retraction of the armature of relay 7, a slow relay 12 is energized and closes the following circuit for the escape magnet 13 of the connector side switch: free pole of battery, magnet 13, 5 arm 4 and its first contact, right armature and front contact of relay 12, conductor 14, armature and back contact of ringing cut-off relay RCO to ground. The escape magnet is constructed to release the side switch 10 from position to position upon its deenergization in the well-known manner. When the sender *s* restores and maintains the stepping relay 7 energized, relay 12 after an interval becomes deenergized, opening the 15 circuit of escape magnet 13, which in deenergizing releases the side switch into position 2. In this position arm 3 substitutes the secondary magnet 15 for the primary magnet 10 in the stepping circuit. 20

25 The calling party now operates his sender *s* to transmit the units digit of the wanted number. Upon each retraction of the armature of relay 7, an impulse is transmitted to the secondary magnet 15 over the circuit previously traced to arm 3, whence it passes to the magnet 15, free pole of battery. Magnet 15 steps the positioned brushes 16, 17 and 18 over the selected group of terminals containing those of the wanted line 19, 25 20, and 21. Upon the first retraction of the armature of relay 7 the slow relay 12 energizes as before, and again closes the circuit of escape magnet 13. When the sender restores and maintains the relay 7 energized, 30 relay 12, after an interval, becomes deenergized opening the circuit of escape magnet 13 which releases the side switch into position 3. Arm 6, in moving into position 3, grounds the test multiples 21 of the selected 35 line to cause the same to test busy to other connectors, and operates the cut-off relay of such line. In this position magnet 13 is again energized over the following circuit: free pole of battery, magnet 13, arm 5 and its third contact, conductor 14, armature and back contact of relay RCO to ground. Magnet 13 at its armature and front contact 40 connects the source of signaling current 22 to the called line over the following circuit: 45 free pole of generator 23 or battery 24, dependent upon the position of the signaling apparatus 22, commutator brush 25, relay RCO, armature and front contact of magnet 13, arm 2 and its third contact, brush 17, 50 multiple 20, bell 25, condenser 26, multiple 19, brush 16, arm 1 and its third contact, conductor 27, armature and front contact of relay 7 to ground. When the called party removes his receiver, relay RCO energizes and 55 opens the circuit of escape magnet 13, 65 which, in deenergizing, releases the side switch into position 4. In position 4, talking current is supplied to the called line over the following circuit: free pole of battery, left winding of relay 28, conductors 29, 30, arm 1, brush 16, multiple 19, through the telephonic apparatus at substation B, multiple 20, brush 17, arm 2 and its fourth contact, conductors 31, 32, right winding of relay 28, to ground. Relay 28 in attracting 75 its right armature interposes a break in the circuit of release magnet RM. The subscribers may now converse. 80

Upon the conclusion of the conversation the parties replace their receivers, which results in the closure of the circuit of release magnet RM as follows: free pole of battery, right winding of magnet RM, conductor 33, armature and back contact of relay 28, off-normal contact PON, conductor 36, left 85 armature and back contact of relay 8, conductors 37, 38, left armature and back contact of relay 28, inner right armature of relay 8, to ground at the armature and back contact of relay 7. When the connector brush shaft 90 reaches its normal position the contact PON opens and the release magnet is deenergized. The deenergization of relay 28 applies ground to release conductor 9, over the right armature and back contacts of relays 7 and 95 8, and the left armature and back contact of relay 28, assuming that the called party has replaced his receiver. If, however, the called party has not replaced his receiver, an impulse is transmitted to the release 100 magnet 123 over the following circuit: armature and back contact of relay 7, right armature and front contact of slow relay 8, which maintains its armatures attracted for an interval after its circuit is broken by the retraction of the armature of relay 7, conductors 11, 39, left armature and front contact of relay 28, conductor 38 to conductor 9. This ground applied to conductor 9, energizes release magnet 123 of the selector 110 S'. The replacement of the receiver by the calling party deenergizes repeating relay 150 which opens the circuit of slow relay 151, which at its armature and back contact closes the circuit of the release magnet 102 115 of selector S and of any other similar selectors. 120

Assume that the calling party upon the conclusion of the conversation desires to talk with a subscriber in the same office in which the line of the party with whom he has just been speaking terminates. In this event the calling party does not replace his receiver but operates the sender *s* to transmit any digit, for example, 1. This interrupts the circuit of repeating relay 150, which, in retracting its right armature, deenergizes relay 7 at the connector. Relay 7 in retract- 125

ing its armature energizes the slow relay 12 over the following circuit: free pole of battery, relay 12, right armature and front contact of relay 8, armature and back contact 5 of relay 7 to ground. Relay 12 in attracting its right armature closes the following circuit for the relay 60: armature and back contact of relay RCO, right armature and front contact of relay 12, arm 4 and its 10 fourth contact, conductor 34, right winding of relay 60 to ground. Relay 60 in attracting its armature closes the release circuit of the selector S' as follows: grounded right armature of relay 60, release conductor 9, 15 139, multiple 181, brush 128, arm 120 and its third contact, release magnet 123 to free pole of battery. This ground would also close circuits in parallel with magnet 123 at each of the selectors equivalent to S'. 20 Magnet 123 in energizing releases selector S' and also restores the associated side switch. The restoration of selector S' deenergizes relay 7 which causes the energization of the release magnet RM of the connector over the following circuit: free pole 25 of battery, right winding of magnet RM, right armature and back contact of relay 28, off-normal contact PON, conductors 36, 44, left armature and back contact of relay 8, conductors 37, 38, left armature and back contact of relay 28, inner right armature and back contact of relay 8, armature and back contact of relay 7 to ground. When 30 the connector brush shaft reaches its normal position, contact PON is opened and the release magnet is deenergized. The connector release magnet in restoring restores the side switch.

During the operations just described the 40 slow relay 151 has been maintained continuously energized, and consequently the selector at the originating office has not been released. The calling subscriber now transmits the necessary number of sets of impulses to set a train of switches to connect with another called line. These operations are the same as the above operations and will not, therefore, be described again.

In case the calling party in setting up the 50 first connection receives the busy signal, due to the engaged condition of the wanted line, he may restore the switches at the distant office without restoring those at the office to which he belongs, and reset a train of 55 switches at the distant office on the line of another party. The operations in this event are as follows: Upon the restoration of the sender *s* after having transmitted the impulses corresponding to the units digit, relay 60 7 remains energized, and after an interval, slow relay 12 becomes deenergized. The retraction of the left armature of this relay closes the circuit of release magnet RM of the connector as follows, the multiple 21 65 being grounded, since the substation B is

busy: free pole of battery, right winding of magnet RM, conductor 33, right armature and back contact of relay 28, contact PON, left armature and back contact of relay 12, conductor 42, arm 6 and its second contact, 7 brush 18, to grounded test multiple 21. This circuit is closed before the left armature of relay 12 is retracted long enough to deenergize the escape magnet 13, this magnet being made slow for this purpose. Release magnet RM in attracting its left armature locks itself to ground at the outer right armature of relay 8, and in attracting its inner right armature applies busy tone from a busy-tone apparatus to talking conductor 81 31, and thence to the calling line. The calling party desiring to set up a connection with another subscriber in the distant office now operates his sender without replacing the receiver. Relay 12 in attracting its 85 right armature in response to the operation of the sender closes the following circuit for the relay 60: free pole of battery, left winding of relay 60, outer armature and front contact of magnet RM, arm 4 and first 90 contact, right armature and front contact of relay 12 to ground at the armature and back contact of relay RCO. Relay 60 in attracting its armature grounds release conductor 9, from which the release magnets of 95 the selectors at the office in which the called line terminates are branched off. These switches release as described.

The calling party then, by means of the sender, operates the repeating relay 150 and builds up a connection to the line of another subscriber as described.

In case the called party fails to respond to the ringing of the bell 25, the calling party by operating his sender momentarily 10 deenergizes relay 7 as described, which transmits an impulse to slow relay 12. Relay 12 in attracting its right armature transmits an impulse over the following circuit to relay 60: free pole of battery, right winding of relay 60, conductor 34, arm 4 in its third contact, right armature and front contact of relay 12 to ground at the armature and back contact of relay RCO. Relay 60 in attracting its armature grounds the release conductor 9 from which the selector release magnets are branched off, whereupon these selectors are restored. The restoration of selector S' results in the restoration of the connector. The calling party may now 11 build up a connection with another line as described.

If the calling party fails to replace his receiver, the called party can secure the attention of an attendant at the exchange by 125 actuating his receiver hook, which causes the intermittent illumination of a lamp 40 over the following circuit: free pole of battery, right winding of magnet RM, conductor 33, right armature and back contact of 130

- relay 28, arm 41, lamp 40 to ground. The release magnet does not operate when this circuit is closed, due to the resistance of lamp 40.
5. What is claimed is:
1. In a telephone exchange system, the combination with telephone lines, offices wherein said lines terminate, link circuits interconnecting said offices including automatic switches, means for setting said switches to interconnect a line in one office with a line in a distant office, and means controlled by the calling party for restoring all the switches or for restoring the switches 15 at the distant office only, and for setting switches therein to connect with another line.
  2. In a telephone exchange system, the combination with telephone lines, offices 20 wherein said lines terminate, two-wire link circuits interconnecting said offices including automatic switches, means for setting said switches to interconnect a line in one office with a line in a distant office, and means controlled by the calling party for restoring all the switches or for restoring the switches at the distant office only, and for setting switches therein to connect with another line.
  3. In a telephone exchange system, the combination with telephone lines, offices wherein said lines terminate, link circuits interconnecting said offices including automatic selector and connector switches, a 35 sender at the calling substation for setting said switches to extend the calling line to a line in a distant office, a manual switch associated with said sender, means operated in one manner by said manual switch to release 40 all of said switches and in another manner by said sender after connection is made with the called line to release the switches at the distant office only, whereupon another connection may be built up over the set switches 45 in the originating office and other switches in the distant office.
  4. In a telephone exchange system, the combination with telephone lines terminating in different offices, trunk circuits inter- 50 connecting said offices and including selectors and a connector, a sender for controlling said switches, a set of repeating relays comprising a fast and a slow relay in said trunk leading to the called office and operated by 55 said sender to set the switches thereat, a release circuit for the switches in the calling office controlled at a back contact of said slow relay, a fast stepping relay at said connector, a circuit therefor controlled at a 60 front contact of said fast repeating relay, a first and second slow relay at said connector controlled respectively at front and back contacts of said stepping relay, a release circuit for the switches at the called 65 office controlled at a back contact of said first slow relay, a second release circuit for the switches at the called office controlled at a front contact of said second slow relay, means for preparing said circuit actuated when the connector is set on the called line, 70 said sender when actuated after the connector is established momentarily deenergizing said fast repeating relay to render said fast relay at the connector momentarily inert whereupon the second slow relay is 75 operated to close said second release circuit to restore the switches at the called office, and a manual switch associated with said sender for permanently opening the line circuit, whereupon the maintained deenergization of the fast repeating relay and fast stepping relay causes the deenergization of their associated slow relays which in deenergizing close the release circuits at both 80 offices.
  5. In a telephone exchange system, the combination with telephone lines, connecting circuits including automatic switches adapted to interconnect said lines and restoring means for each of said switches, of 85 means under the control of the calling party for actuating the restoring means of all of said switches, or for actuating the restoring means of the switch connected to the called line and of a number of preceding switches 90 only, and for setting up a connection to another called line over the set switches and other switches.
  6. In a telephone exchange system, the combination with calling and called telephone lines, a connector wherein said lines terminate, trunk circuits including selectors, a sender for controlling said selectors to effect connection to said connector over said 100 trunk circuits, and to set the same on a called line, a manual switch, restoring magnets for said switches, means associated with said connector adapted to be operated in one manner by said manual switch to cause the actuation of all of said restoring magnets, 105 and to be operated by said sender in another manner after the connection has been established to actuate the connector restoring magnet and certain only of the selector restoring magnets.
  7. In a telephone system, the combination with telephone lines, connecting circuits including automatic numerical switches for interconnecting said lines, means controlled at the calling station for restoring a part 110 only of the selectors involved in a connection and for controlling other selectors over the unrestored switches to build up another connection.
  8. In a telephone system, the combination with telephone lines, automatic switching means for interconnecting said lines, means controlled at the calling station for restoring a part 115 only of the automatic switching means involved in a connection and for employing 120

the remaining part in building up another connection.

9. In a telephone system, the combination with telephone lines, automatic switching means for interconnecting said lines, means controlled at the calling station for restoring a part only of the automatic switching means involved in a connection, and for em-

ploying the remaining part in building up another connection, and for restoring all of the automatic switching means involved in the connection.

In witness whereof, I hereunto subscribe my name this 9th day of October, A. D. 1916.

CHARLES L. GOODRUM.
